UNITED STATES PATENT OFFICE.

STEPHEN D. SMITH, OF SPOTSWOOD, NEW JERSEY.

CAR-CO尤LING ATTACHMENT.

SPECIFICATION forming part of Letters Patent No. 374,714, dated December 13, 1887.

Application filed May 16, 1887. Serial No. 238,392. (No model.)

To all whom it may concern:

Be it known that I, STEPHEN D. SMITH, of Spotswood, in the county of Middlesex and State of New Jersey, have invented a new and 5 Improved Car-Coupling Attachment, of which the following is a full, clear, and exact description.

This invention relates to an attachment whereby cars provided with what is technically termed "three-link coupling" may be coupled without requiring the train-men to enter the space between the approaching ends of the cars to be coupled; and to the end named the invention consists of a folding frame, a 15 lever carried by said frame, and a nose pivotally mounted within the frame and arranged to support the free end of the outer coupling-link and to be held in position by the lever, all as will be hereinafter described, and specifically pointed out in the claims.

Reference is to be had to the accompanying drawings, forming a part of this specification, in which similar figures of reference indicate corresponding parts in all the views.

Figure 1 is a side view of a portion of two cars, representing one of said cars as it appears when provided with my improved coupling attachment, the parts being represented as they appear just after the cars have been moved 30 to a position to bring the coupling-link above the draw-hook of the adjacent car. Fig. 2 is a plan view of a portion of two cars, one of which is provided with my improved coupling, the cars being represented as they appear just prior to the time they reach the coupling position; and Fig. 3 is a side view in 35 partial section, representing the parts as they appear after the coupling of the cars has been brought about.

In the drawings above referred to, 10 and 40 11 represent the draw-hooks and 12 the coupling-chain of that class of coupling to which my invention is applicable. Above the draw-hook 10 I mount a case, 13, in which there is 45 hinged a folding arm, 14, connection between the arm and the case being established by a hinge, 15.

The end of the arm 14 is slotted, and in the 50 slot so formed there is pivotally mounted a double-ended nose, 16, said nose being formed with recesses 17 at diagonally-opposed corners. In connection with this nose there is

pivotedly connected to the arm 14 a lever, 18, the forward end of which is somewhat enlarged and formed with a central recess, 19, a sheathing, 20, being arranged about the forward end of the lever and serving as a guide for the pivot pin or bolt 21, by which the lever is connected to the arm. This lever 18 is provided with a folding handle, 22, said handle being 60 connected to the main body of the lever by a hinge, 23. When not in use, the handle 22 is folded back to the position in which it is shown in Fig. 3, and then the arm 14 and the parts carried thereby may be turned up so as 65 to rest within the case 13, any proper retaining attachment being employed to support the parts in this position. When, however, it is desired to couple cars by means of the attachment, the arm is turned down to the position 70 in which it is shown in the drawings, and the free end link 2 of the chain 12 is placed upon the nose 16, the link at this time resting within one of the recesses 17, the lever 18 being turned so that one of the spurs or projections 75 at either side of the recess 19 will bear against the upper face of the inner end of the nose, the lever and its handle extending diagonally outward toward the corner of the car within reach of the train-men. Then, as the cars come 80 to the position in which they are shown in Fig. 1, the train-men will move the lever inward in the direction of the arrow shown in connection therewith in Fig. 2, thus throwing the spur of the lever from engagement with the 85 nose 16, immediately after which the weight of the chain will tilt the nose to the position in which it is shown in Fig. 3 and the link 2 will drop into engagement with the hook 11, the inner end of the nose passing up through 90 the recess or aperture 19 of the lever 18.

From the construction described it will be seen that the coupling of the cars may be brought about from either side of the train, and that all necessity of entering the space 95 between the cars is avoided.

Having thus fully described my invention, I claim as new and desire to secure by Letters Patent—

1. In a coupling attachment, the combination, with a supporting-arm, of a nose pivotally mounted therein, and a nose-tripping mechanism, substantially as described.
2. In a coupling attachment, the combina-

tion, with a supporting-arm, of a nose pivotally connected thereto, and a lever formed with a recessed end, said lever being pivotally connected to the supporting-arm and arranged 5 to engage with the nose, substantially as described.

3. In a coupling attachment, the combination, with a supporting-arm, of a nose, 16, formed with a recess, 17, and pivotally connected to the arm, a lever, 18, formed with a recess, 19, and arranged to engage with the nose 16, and a sheathing, 20, substantially as described.

4. In a coupling attachment, the combination, with a case, 13, of an arm, 14, hinged 15 thereto, a lever, 18, formed with a recess, 19, and pivotally connected to the arm 14, a handle, 22, hinged to the lever, and a nose, 16, formed with recesses 17 and pivotally mounted within a slot formed in the extending end of 20 the arm 14, all substantially as described.

STEPHEN D. SMITH.
